UNITED STATES PATENT OFFICE.

HARRY C. KETTELSON, OF MILWAUKEE, WISCONSIN.

ROOFING-CLEAT.

1,273,500.

Specification of Letters Patent. Patented July 23, 1918.

Application filed April 20, 1917. Serial No. 163,350.

To all whom it may concern:

Be it known that I, HARRY C. KETTELSON, a citizen of the United States, and resident of Milwaukee, in the county of

5 Milwaukee and State of Wisconsin, have invented certain new and useful Improvements in Roofing-Cleats; and I do hereby declare that the following is a full, clear, and exact description thereof.

10 My invention relates to new and useful improvements in elongated metallic cleats adapted for securing roofing sheets to the roof boards of buildings.

Such cleats heretofore contemplated are 15 provided with bracing means comprising one or more longitudinally extending ribs struck upwardly from the body of the cleat and which possess the disadvantage of permitting accumulation of water in the consequent pocket formed in the cleat thus 20 permitting rusting of the cleat and nails, and which possess the further disadvantage of obstructing the passage of water over the roofing. Therefore the ideal cleat would 25 comprise an entirely flat cleat plate, but the provision of a flat cleat plate with sufficient stiffness to procure a clamping action throughout its length is commercially impractical.

30 In view of the foregoing it is primarily the object of my invention to provide a roofing cleat having longitudinal bracing means so disposed as to eliminate the disadvantages of the upstanding bracing ribs 35 heretofore provided, and more specifically my invention consists in providing the sole bracing means of the cleat in the form of a laterally turned flange at one side edge thereof, whereby said flange may lie within

40 the recess afforded by the lapped end of the uppermost sheet of roofing material to permit the entire remaining portion of the cleat to lie flat upon the sheet of roofing, this flange portion incidentally serving also 45 as a seal for the seam provided by the lapped ends of the roofing sheets.

Inasmuch as roofing sheets may differ considerably in thickness, such sheets being supplied in differing plies, it is further an object to provide an arrangement whereby the flange portion is resiliently adjustable to accommodate such differing thicknesses of roofing material.

With the above and other objects and 55 advantages in view, the invention resides more particularly in the novel combination,

formation and arrangement of parts, hereinafter described and pointed out in the appended claim.

In the drawings:

Figure 1 is a plan view of a roofing cleat constructed in accordance with my invention.

Fig. 2 is a longitudinal sectional view through the cleat on the line 2—2 of Fig. 1, 65 showing more particularly the flat nature of the body of the cleat.

Fig. 3 is a transverse sectional view through the cleat on the line 3—3 of Fig. 1.

Fig. 4 is a transverse sectional view 70 through the cleat on the line 4—4 of Fig. 1.

Fig. 5 is an enlarged sectional view taken transversely through the cleat and showing more particularly the resilient adjustment of the bracing flange and seal.

Fig. 6 is a detail plan view showing the manner of applying the invention where more than two edges of the roofing material come together, and

Fig. 7 is a detail transverse section on the 80 line 7—7 of Fig. 6.

Referring now more particularly to the accompanying drawings, my improved cleat comprises a flat elongated metallic body plate 5, and one side edge portion 6 of 85 this plate is bent laterally at a right angle, and then curved outwardly, the tangent of the outer extremity of said edge portion being at a slight acute angle to the body of the cleat whereby to yieldably engage an 90 under-most sheet of roofing material in such manner as not to bite into the roofing, nor yet incline away therefrom to form a possible water pocket upon considerable flattening of the flange, due to the relatively slight 95 thickness of roofing material. Any possible danger which otherwise might exist of the edge of the portion 6 cutting into the under-most sheet of roofing is obviated by the slight curvature and spring action of the 100 same, said roofing being engaged only by the bottom surface thereof.

At regularly spaced intervals, the cleat is provided with upwardly struck cup portions 7 centrally apertured to receive the securing nails of the cleat. The provision of the cup portions 7 allows the securing nails to be inserted through the flat body plate 5 without causing the warping of the same. In other words, the cup portions receive and 110 absorb the entire driving strain of the nails.

With the exception of these cup portions

and the bracing flange 6, the cleat is thus entirely flat and when disposed upon roofing as shown more particularly in Figs. 3 and 4, the body 5 rests snugly against the face 5 of the roofing material and the flange 6 which lends sufficient longitudinal stiffness to the cleat is disposed in the recess afforded by the over-lapped edge of the uppermost sheet of roofing material. The edges 10 of the cups 7 form an efficient seal for the space inclosed thereby, and thus the possibility of accumulation of water within the cleat is prevented and at the same time the body of the cleat does not obstruct the passage 15 of water over the roofing, as in those types of cleats including rib portions upstanding from the body plane of the cleat.

When more than two pieces of roofing material over-lap the cleats are arranged 20 somewhat as shown in Figs. 6 and 7. In this case the longitudinal cleat 5' has its flange 6' slit as shown at 8 to compensate for the change in elevation between one portion 25 of the roofing material and the over-lapping piece. This slit is thus made at the point where the edge of one piece of roofing material intersects the edge of the other. The end of the transverse cleat 5'' has its 30 end cut off at an angle to correspond with the inclination of the longitudinal cleat 5' with respect to the edge of the piece of roofing material which the former cleat is designed to overlie. Both of the cleats are 35 held in position by suitable fastening elements as above mentioned, and it is obvious that a very simply constructed water-tight joint is formed.

I am aware that it has been heretofore contemplated to provide a laterally turned 40 flange portion at the side edge of the cleat

for sealing the seam provided by the over-lapped edges of roofing sheets, but such a laterally turned flange has not been employed in connection with an otherwise entirely flat cleat body to utilize the bracing 45 function inherent in the laterally turned flange.

A further advantageous feature of my cleat is the adjustment of the laterally turned flange portion for differences in 50 thickness in roofing material in contra-distinction to heretofore contemplated flange portions which are either of a rigid nature or adapted to bite into the under sheet of roofing material, such biting action being 55 harmful to the roofing material, more particularly in view of the relatively greater pressure which would be incidental to a slight thickness of the upper sheet of roofing material. 60

What is claimed:—

A roofing cleat comprising a flat elongated body plate adapted to lie snugly against an uppermost sheet of roofing material without cutting into the same, said body plate having a nail receiving cup portion struck therefrom whereby to relieve the flat portion of the plate from the driving strains of the nail to prevent it from warping, and a downwardly extending 70 transversely curved flange formed on one longitudinal edge of the body plate, said flange being adapted to have its underside surface yieldingly engaged with an undermost sheet of roofing material. 75

In testimony that I claim the foregoing I have hereunto set my hand at Milwaukee, in the county of Milwaukee and State of Wisconsin.

HARRY C. KETTELSON
